UNITED STATES PATENT OFFICE.

JULIUS W. FLEISCHMANN, OF WILLIAMSBURG, NEW YORK.

DESIGN FOR PIPE-STEMS.

Specification forming part of Design No. 7,956, dated December 22, 1874; application filed December 17, 1874.
[Term of Patent 3½ years.]

To all whom it may concern:

Be it known that I, JULIUS W. FLEISCHMANN, of Williamsburg, in the county of Kings and State of New York, have invented certain new and useful Improvements in Design for Pipe-Stems; and I do hereby declare that the following is a full, clear, and exact description thereof, which will enable others skilled in the art to which it pertains to make and use the same, reference being had to the accompanying drawings, and to the letters of reference marked thereon, which form a part of this specification.

This invention relates to a new design for an improved pipe-stem of ornamental form, and is fully illustrated in the accompanying drawing, in which the figure represents a side elevation of my improved design.

A represents the stem, provided with any desired form of mouth-piece, a, from which

the stem gradually increases in size to the opposite end, which is provided on the upper side with enlargements, B, for the bowl, while the receptacle on the lower side is made in the form of an acorn, as shown in the drawing.

Having thus fully described my improved design for pipe-stem, what I claim as new, and desire to secure by Letters Patent, is—

The improved design for pipe-stems, as shown, consisting of the stem A, enlargement B, and lower receptacle C, in form of an acorn, all as and for the purpose herein set forth and shown.

In testimony that I claim the foregoing as my own, I affix my signature in presence of two witnesses.

JULIUS W. FLEISCHMANN.
